PUMP PACKING

William N. Weinman, Columbus, Ohio

Application March 1, 1935, Serial No. 8,922

4 Claims. (Cl. 286—34)

This invention relates to improvements in pump packings and has for its object the provision of an improved packing by which the escape of liquid from the associated pump housing through the joints surrounding the operating shaft of the pump is effectually precluded. Other objects of the invention are: the provision of a packing for surrounding a rotatable shaft wherein the rings of compressible material, formed in connection with the packing, are placed under compression by a follower mounted to move longitudinally of the associated shaft to compress the packing by a straight longitudinal movement to prevent binding strains or stresses from being imparted to the shaft and interfering with its desired rotary motion; the provision of a packing wherein the follower advances into engagement with the packing by the action of an internally threaded nut which is disposed concentrically with respect to the longitudinal axis of the associated shaft; a packing provided with means for maintaining a liquid seal therein to prevent the passage of atmospheric air through the packing and into the housing of the pump; in the provision of a packing which may be easily and readily adjusted to maintain the compressible packing materials under desired compression; in the provision of means for preventing the escape of liquid through the packing when the shaft is stationary and high back pressures exist on the fluid in the associated pump housing; in the provision of a packing of the threaded type which will retain its compression irrespective of the direction of rotation of the pump shaft; and in the provision of a packing particularly suitable for the protection of an electric motor when the latter is employed to drive directly the shaft of the pump and is disposed in relatively close proximity to the pump housing.

Other objects will be in part obvious and in part pointed out hereinafter.

For a further understanding of the invention, reference is to be had to the following description, the accompanying drawing and the appended claims.

In said drawing:

- Fig. 1 is a perspective view of an electric motor driven pump, the latter being provided with a packing comprising the present invention;
- Fig. 2 is a vertical sectional view through the motor driven centrifugal pump, the packing comprising the invention being disclosed in elevation;
- Fig. 3 is a vertical longitudinal sectional view taken through the packing;
- Fig. 4 is a transverse vertical sectional view of

the packing on the plane indicated by the line IV—IV of Fig. 3;

Fig. 5 is an enlarged detail longitudinal sectional view taken through the packing.

Referring more particularly to the drawing, the numeral 1 designates the casing of a pump, the latter being shown in this instance as of the centrifugal type and is formed internally with an impeller 2 formed with an axial liquid inlet 3 which communicates with a plurality of outwardly and radially disposed nozzles 4, the inlet 3 being arranged in registration with the open end of a liquid supply pipe 5 threaded in the hub extension 6 of the casing 1, there being a wear-receiving ring 7 disposed between the impeller and the hub 15. The impeller is further formed with a hub 8 which receives the reduced outer end 9 of the armature shaft 10 of an electric motor 11, which may be of the reversible type. The casing 1 is also provided with a tangentially disposed liquid outlet 12, shown as provided with a discharge pipe 13. The field frame 14 of the motor 11 is provided with a tubular extension 15 which is disposed between the motor 11 and the pump casing 1 by which the pump casing may be secured 25 rigidly but separately with the motor frame.

In a pump arrangement of this character, considerable difficulty has been encountered in maintaining the packing which surrounds the motor shaft sufficiently tight to overcome leakage 30 through the packing and its injurious contacting with the operating parts of the motor 11. Usually, these motors operate at high speeds and if there is but small leakage through or past the packing, the same is apt to be disseminated in 35 the form of a spray over the motor. The usual packing comprises a follower for placing the compressible material of the packing under compression. It has been customary to provide the opposite and outer sides of this follower with openings 40 for the reception of spaced stud bolts projecting rigidly from the pump casing and equipped with nuts or other threaded devices which are separately actuated to draw the follower into desired clamping engagement with the compressible 45 packing rings. As a matter of practice, it is difficult to tighten the securing members for the follower on both sides thereof to an equal degree, but unless this is done, the follower does not move inwardly in a straight longitudinal line in true 50 concentric relationship with the pump shaft, the result being that laterally directed pressures and undue friction is applied to the motor shaft causing excessive wear thereof and a packing which does not confine liquid to the pump casing. 55

In order to improve this customary packing construction and to overcome the objections which I find inherent in them, the inner vertical wall 16 of the casing 1 is formed around the shaft 10 with a box extension 17, which is disposed concentrically with respect to the shaft 10 and is suitably spaced therefrom to produce an annular packing-receiving socket 18. Rotatable with the shaft 10 is a pressed-on sleeve 19 which at its forward end engages with the impeller hub 8 of the pump, the sleeve 19 rotating in unison with the impeller and its operating shaft. Surrounding the outer portion of the sleeve 19 and disposed within the socket 18 are packing rings 20 of suitable compressible materials, the said rings being also received within a cage 21 positioned in the socket 18 around the sleeve 19. The inner end of said cage is provided with a flange 22 which engages with the sleeve 19, an annular recess being formed thereby between the sleeve 19 and the cage 21 for the reception of the packing rings 20, the inner of said packing rings engaging with the flange 22, as disclosed in Fig. 3.

The forward end of the cage 21 is provided with an outturned annular flange 23, the outer face of which is formed to engage with a key ring 24. The peripheral portion of the ring 24 is provided with radially projecting lugs 25, which are received within recesses 26 provided in connection with the outer portion of the flange 23, as shown in Fig. 4. Likewise, the ring 24 is provided with an inwardly projecting key lug 27 which is disposed to be received within a longitudinally extending slot 28 provided in connection with a threaded follower 29. This follower comprises a tubular metallic member which is externally threaded as at 30 and has its inner tubular end disposed to enter the annular recess formed between the sleeve 19 and the cage 21, whereby to press directly upon the packing rings 20. The outer end of the follower terminates in an annular enlargement 31, in which is formed an annular recess 32, surrounding the shaft 10. The enlargement 31 of the follower includes a socket for the reception of a fibrous ring washer 33, which is removably held within the recess 32 by a threaded ring 34 carried by said follower.

Mounted upon the threaded end 30 of the follower is an adjusting collar 35, which is internally threaded as at 36 for the reception of an externally threaded ring 37, the latter being disposed for engagement with the rear surface of the flange 23 of the cage 21, thereby preventing longitudinal travel of the collar 35 when the latter is rotated with respect to the follower, since the cage 21 has a press fit in the socket 18 formed in the extension 17. It will be seen, however, that by rotating the collar 35, longitudinal movement will be imparted to the follower 29 since the latter has threaded connection as at 30 with the collar 35, and in view of the fact that the follower 29 can not rotate due to the interposition of the keyring 24. Thus the rotation of the collar 35 merely causes the follower 29 to move longitudinally of the shaft 10 and in true coaxial relationship therewith, thereby compressing or releasing pressure upon the packing rings 20. In effect, therefore, the collar 35 has a swiveled connection with the outer end of the pump box 17.

If desired, the cage 21 may be provided intermediate of its length and on its outer surface with a shallow annular groove 38, which registers with a plurality of longitudinally aligned ports 39 arranged in registration with a ported metallic lantern ring 40, which is disposed between the pack-

ing rings 20. A pipe 41 may unite the outlet 12 of the casing 1 with the interior of the box extension 17 at a point in registration with the groove 38. This allows liquid under high pressure from the discharge side of the pump to enter the groove 38, thence through the ports 39 and through the ports of the ring 40 into contact with the sleeve 19. This serves to produce a liquid seal in the packing which prevents air drawn from the atmosphere from passing into the interior of the pump when the latter is operating under conditions causing the formation of a high vacuum. The ring washer 33 in the outer end of the follower is also of material value in protecting the motor 11 when the pump is not operating. Frequently, there exists on a pump of this kind a high hydrostatic back pressure which tends to cause the discharge of liquid through the packing toward the motor. Any back pressure liquid which finds its way through the packing and into the groove formed internally of the annular enlargement 31 of the follower is obstructed by the ring washer and prevented from escaping from the packing.

It will be observed that in the operation of the packing, in order to tighten or compress the rings 20, it is necessary merely to rotate the collar 35, which being swiveled on the outer end of the cage 21, a stationary member, causes the longitudinal movement of the follower 29 in a true axial and longitudinal direction with respect to the shaft 10, thus relieving the shaft of undue binds, friction or pressure by reason of the tightening of the packing. The shaft may rotate in either direction without interfering with the utility of the packing even though an annular threaded member is employed for placing the packing rings under compression.

While I have described what I consider to be the preferred form of my invention, nevertheless it will be understood that the same is subject to considerable change and modification without departing from the essential features of the present invention, as the latter have been defined in the following claims.

What is claimed is:

1. A packing comprising a casing formed for the reception of a rotatable shaft, there being an open-ended socket provided between the internal walls of said casing and said shaft, a sleeve non-rotatably positioned in said socket and having the outer face thereof provided with a recess, packing members of a compressible material surrounding said shaft and disposed between the latter and said sleeve, an exteriorly threaded follower positioned upon said shaft and movable longitudinally with respect thereto to regulate the compression of said packing members, a rotatable collar having a threaded axial opening for the reception of the threads of said follower, and a key ring having inwardly and outwardly projecting lugs, the outwardly projecting lug of the key ring being received within the recess of said sleeve and the inwardly projecting lug of said ring being received within a longitudinally extending slot provided in said follower.

2. A packing comprising a casing for the reception of a rotatable shaft, there being an annular open-ended socket provided between said casing and said shaft, a non-rotatable sleeve positioned in said socket, said sleeve terminating at one end in an outwardly directed flange having a recess provided in its outer face, a collar swiveled for rotation in connection with said flange, an exteriorly threaded tubular follower

movable longitudinally of said shaft, packing members of compressible material disposed between said sleeve and said shaft and engaged by one end of said follower to regulate the compression of said members, said follower being threadedly received within an axial opening provided in said collar, and a ring having outwardly and inwardly projecting lugs, the outer of said lugs being received within the recess provided in the outer flange of said sleeve, the inner of said lugs being received within a longitudinal slot provided in said follower.

3. A stuffing box comprising a sleeve member provided with an open ended, concentric socket, said sleeve having an external flange formed upon its socketed end, said flange having a recess formed therein, an internally threaded collar, means for swivelling said collar to the flanged end of said sleeve, an externally threaded follower carried by said collar and slidable in the socket in said sleeve, said follower being provided with a recess, and a washer member provided with internal and external projections

positioned between the flange on said sleeve and said collar, said projections being positioned in the recesses in said flange and follower and serving to lock said follower in non-rotatable relationship with said sleeve.

4. A stuffing box comprising a sleeve member provided with an open ended socket, an external flange formed with the socketed end of said sleeve, said flanged end of said sleeve being provided with a radially extending recess, an externally threaded follower slidably received within the socket in said sleeve, said follower having a longitudinally extending recess formed in its outer wall, key means positioned in the recesses in said flange and follower for connecting said follower and sleeve in non-rotating relationship, and an internally threaded collar swivelled to said flange and serving to move said follower into and out of the socket in said sleeve and to confine the sleeve and follower connecting means in the recess in said flange.
